TONGS FOR GAME PIECES

Harry D. Dodd, Edward M. Anderson, and
Tolleson C. Parker, Inman, S. C.

Application March 18, 1939, Serial No. 262,700

1 Claim. (Cl. 294—99)

The present invention appertains to new and useful improvements in amusement apparatus and more particularly to an implement in the nature of tongs whereby game pieces, such as the marbles or spheres employed in the game of "Chinese checkers" can be handled in a convenient and accurate manner in the operation of making moves, during the course of playing the game.

10 The principal object of the present invention is to provide a simple and inexpensive appliance which can be used in handling game pieces, to the end that very little effort will be required of the player, and also to the end that the player 15 in making moves will not inadvertently disturb other game pieces, which situation occurs very frequently in the playing of the present popular game of "Chinese checkers."

Other objects and advantages of the invention 20 will become apparent to the reader of the following specification.

In the drawing:

Figure 1 represents a fragmentary sectional view through a "Chinese checker board," on 25 which are several game pieces, one of which is engaged by the device of the present invention.

Figure 2 is a fragmentary top plan view of the invention.

Figure 3 is a perspective view.

30 Figure 4 is a perspective view of a modified form of the invention.

Referring to the drawing wherein like numerals designate like parts, it can be seen that numeral 5 generally refers to the game board 35 which in the game of "Chinese checkers" generally consists of the base ply 6 and the superimposed perforated ply 7, this latter ply being perforated to form marble receiving pockets 8 in which the marbles 9 and from which the 40 marbles can be taken and placed in other pockets as moves are made during the playing of the game.

In carrying out the present invention an implement has been devised whereby these marbles 45 can be lifted singly from pocket to pocket, with the minimum amount of likelihood that other marbles will be disturbed, which now frequently occurs as the free fingers of the player's playing hand sweep against marbles in moving a marble from one position to another.

50 This implement which is generally referred to by numeral 10 constitutes the present invention and the first form is shown in Figures 1, 2 and 3, while a second form is shown in Figure 4.

55 In construction, this implement consists of a

U-shaped handle member of spring wire or rod material, this handle including the leg portions 11 and 12. The leg portion 12 is curved downwardly and then upwardly to form the downwardly offset jaw loop 13 at its free end, while the leg portion 11 adjacent its free end is curved downwardly as at 14 and then upwardly as at 15 to form a complementary jaw loop. The upwardly curved portion 15 is brought across the leg portion 11 as at 16 and then extends across 5 to the other leg 12, and over this leg 12 the end portion of the leg 11 is bent as at 17 and extended backwardly as at 18 in spaced relation to its bridge portion 19, thus forming a guide in which the jaw end portion of the leg 12 can operate. 10

The tension of the leg portions 11 and 12 is such, that the leg 12 will always abut the bight 17, so that the jaws 13 and 14 will always be in sufficient spaced relation to embrace a checker game piece 9. When the jaws 13 and 14 are 20 properly disposed laterally with respect to the game piece 9, the player squeezes the leg members 11 and 12, thus drawing the jaw members 13 and 14 together against the game piece 9 and thus holding the game piece, the game piece can 25 be lifted and moved to whatever other pocket 8 desired. The guide means 18—19 serves to prevent any offsetting of one jaw with respect to the other.

This latter provision, namely, the guide means 30 18—19 is absent in the second form of the invention shown in Figure 4.

This second form of the invention is generally referred to by numeral 20 and consists of a U-shaped spring wire or rod element having the leg 35 portions 21 and 22.

The free end portion of each leg is bent downwardly and then upwardly, below the plane of the corresponding leg 21 or 22 to form the loop-shaped jaw 23. Normally, these jaws 23—23 are 40 sufficiently spaced apart so that they can conveniently be disposed into position at opposite sides of a game piece 9, after which the leg members 21 and 22 can be contracted to bring the jaws 23—23 into clamping relation with the game piece, preparatory to lifting and moving 45 the game piece to a new position.

At this point it will be noted that in both forms of the invention the jaws are offset downwardly, in each instance below the plane of the corresponding leg members. The object in offsetting these jaws downwardly is to afford as much clearance as is possible between the fingers of the player's hand holding the implement and the underlying game pieces on the board. 50

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

10 Tongs for game pieces comprising a U-shaped member of spring material having game piece engaging loops at its free end, said loops consisting in construction of the disposition of the end portions of the U-shaped member down-

wardly in a curved form from the plane of the U-shaped member and disposing the said end portions backwardly and upwardly, with one end portion terminating in opposed relation to one leg portion of the U-shaped member, while the other end portion is disposed over its corresponding leg portion and then laterally to bridge the other leg portion and from where it extends backwardly to define a guide extension. 5
